The ornamental design for a toast carriage handle, as shown and described.

DESCRIPTION

FIG. 1 is a perspective view as seen from the top, front and left side of a toast carriage handle showing my new design; FIG. 2 is a perspective view similar to FIG. 1 but not showing a fragment of a toaster housing shown in broken lines in FIG. 1;

FIG. 3 is a left side elevational view of the toast carriage handle of FIG. 1, the right side being a mirror image of the left side;

FIG. 4 is a front elevational view of the toast carriage handle of FIG. 1; the rear of the toast carriage handle is unornamented and hidden in normal use; and,

FIG. 5 is a top plan view of the toast carriage handle of FIG. 1; the bottom of the toast carriage handle is flat and unornamented.

The broken lines in FIG. 1 showing a fragment of a toaster housing and in FIGS. 1 and 2 showing depressions on the toast carriage handle are used for illustrative purposes only and form no part of the claimed design.
